United States Patent

Des. 238,791

Patented Feb. 10, 1976

238,791

WALL PLAQUE

Donovan Worland, San Francisco, Calif., assignor to Miller Brewing Company, Milwaukee, Wis.

Filed Nov. 1, 1974, Ser. No. 519,956

Term of patent 14 years

Int. Cl. D11—02

U.S. Cl. D29—23 A

FIG. 1 is a front elevational view of a wall plaque showing my new design;

FIG. 2 is a rear elevational view thereof;

FIG. 3 is a top plan view thereof;

FIG. 4 is a bottom plan view thereof;

FIG. 5 is a left end elevational view thereof; and

FIG. 6 is a right end elevational view thereof.

I claim:

The ornamental design for a wall plaque, as shown.
